UNITED STATES PATENT OFFICE.

THOMAS OGDEN, OF LYNWOOD, CALIFORNIA.

JOURNAL BOX.

Application filed September 6, 1924. Serial No. 736,364.

This invention pertains to journal boxes for railway use, and has reference more particularly to the construction, and manner or means of securing in such boxes, the "cellar" or receptacle which contains the lubricant, and, if such be used, the waste or absorbent material which holds the lubricant and applies it to the journal.

The object of the invention is to produce a journal box the cellar of which shall be practically held against vibration and constantly pressed toward the journal, so that the waste, saturated with lubricant, shall press against the journal and constantly apply lubricant thereto in proper quantity.

The invention is illustrated in the accompanying drawings, in which:

Figure 1 is an end view of the box or bearing, looking from the inner end, the cellar being shown in half section, better to illustrate the construction and arrangement of parts;

Fig. 2, a side elevation, also partly broken away or in section, for a like purpose.

Journal boxes of this character are introduced between the jaws or walls of openings in the frames of locomotives, or of pedestals of railway cars, in which spaces they have vertical movement. The drawing does not show such frame or pedestal since both are of well-known design and do not enter into the invention here sought to be protected.

In the accompanying drawings, 1 designates the journal box; 2 the brass or saddle which rests upon the journal; 3 the journal; 4 the cellar; 5 a spring member by which the cellar is yieldingly supported and pressed toward the journal; 6 a pin or bolt for securing said spring member in place and preventing escape of the cellar in the event that the spring be broken or lost; and 7 a cotter pin passed through the end of the pin or bolt 6 to prevent its accidental escape or withdrawal. The box 1 is of usual design, or substantially so, but has at or near its ends and on either side, downwardly projecting ears 8 perforated for the passage through them of fastening bolts or pins 6.

The cellar 4 is provided near its front and rear ends with horizontal holes or openings 9 extending from side to side in alignment with the holes in the ears 8. The holes 9 are of a size to permit some slight vertical play or adjustment of the cellar 4 relatively to the fastening pins or bolts 6, said holes

being here shown of elliptical form with the major axis in the vertical plane. The cellar 4 is of the design shown in the drawing, that is to say, it is of a generally rectangular box-like form, the lower longitudinal corners of which may be rounded as indicated. Its end walls are cut away to receive the journal 3 and to fit quite closely thereto, the lower end portions being thickened as seen in Fig. 2, to afford sufficient metal or body for the holes 9.

To support and hold in place the cellar 4, there are provided two spring members 5, each of which is carried by a cellar pin or bolt 6, here shown as having one end bent at a right angle to the box to prevent its passing through the holes in the several parts, while the opposite end is pointed to facilitate its entrance into and passage through said holes. Just back of the tapering or conical leading end, each bolt is provided with a transverse slot or flattened opening 10 to receive a cotter-pin 7, the ends of which are slightly bent apart after the pin is inserted in place, to prevent its accidental escape. The spring member 5 is of the form clearly shown in Fig. 1; that is to say, each end is doubled over upon itself to give adequate thickness and prevent cutting into the cellar pin or bolt 6, or undue wearing of the eye or perforations of the spring. At its midlength the spring is bent upward to afford a flat bearing contact with the under side of the cellar, while the portions between the upstanding perforated ends and the central bearing portion, taking the form of easy curves, afford the necessary resiliency.

The cellar 4, supplied with waste if desired, and with a suitable lubricant, is pushed upward between the walls of the journal box until the waste, if such be used, makes close contact with the journal, and the end walls lie close thereto, as indicated in the drawings. When said cellar is raised to its proper height, a spring member 5 is applied at each end of the box and cellar, the cellar pin or bolt 6 being passed first through one arm or end of the spring, thence through an ear 8 of the box, then through the opening 9 of the cellar, the second ear of the box, and the final end of the spring member 5, after which the cotter-pin 7 is passed through the transverse opening of the pin and its free ends are spread as stated. The same operation is performed in

securing the spring 5 in position beneath the cellar at each end thereof, and the device is ready for use.

I am aware that it is not broadly new to 5 construct journal boxes with removable cellars, or to support the same on resilient members. The present design, however, is simple and strong, easy to apply and to remove, and relatively inexpensive to manufacture. It meets all the actual working 10 conditions, and can be applied, or removed and replaced, by inexperienced workmen, quickly and with ease, no special tools being necessary for performing these operations. 15 It will be noted also that the cellar is doubly secured against dropping out so long as the cellar pins or bolts remain in place; that is to say, said pins or bolts will retain the cellar even though the spring members 20 be omitted or lost. In practice, the spring should hold the cellar at such height as to prevent the escape of its contents at its ends, and the holes 9 of the cellar should hence afford clearance below the pins or bolts 25 6 so that the springs may raise the cellar in the event of wear of the end walls of the cellar through contact with the rotating journal. In other words, the springs serve not only to support the cellar but to exert a 30 follow-up pressure thereon which will maintain the curved seats in their end walls close to the journal even though there be wear of said seats or of the perforations in the spring ends or the ears of the box. On the 35 other hand, vibration or chattering of the cellar is precluded, thus reducing wear and preventing noise.

It is obvious that the number of springs and pins may be increased, or that if 40 deemed desirable a single spring at or about the midlength of the cellar could be used, guiding ribs being provided to prevent tipping of the cellar in the direction of its length. The construction shown, however, 45 is deemed best.

When it is desired to introduce fresh lubricant, waste, or both, it is necessary only to remove the cotter pins 7 and withdraw the pins or bolts 6, thereby freeing the 50 springs 5 and permitting removal and recharging of the cellar 4, after which the parts can be quickly replaced by reversing the steps stated for removal.

What is claimed is:—

55 1. In combination with a journal box hav-

ing depending perforate ears, a cellar fitting therein and provided with transverse openings at or near its ends; springs, each having perforate upturned ends to lie close to the outer faces of said ears and a raised portion 60 at its midlength to bear against and support the under side of the cellar; and cellar pins passing through openings in the 65 spring ends, the journal box ears and the cellar, and serving to retain the spring members in the place.

2. In combination with a journal box having depending perforate ears, a cellar fitting therein and provided with transverse openings at or near its ends; springs, each having 70 perforate upturned ends to lie close to the outer faces of said ears and a raised portion at its midlength to bear against and support the under side of the cellar; cellar pins passing through openings in the spring ends, the 75 journal box ears and the cellar, and serving to retain the spring members in place; and means to prevent accidental displacement of the cellar pins.

3. In combination with a journal box of 80 substantially inverted U shape in cross section and provided with transverse perforations at the lower edges of its side walls, a lubricant cellar insertible between the walls of said box; spring members passing beneath the cellar and having upturned ends provided with perforations registering with those of the box; and cellar pins or bolts passing through the perforations of the 85 springs and of the journal box and beneath 90 the cellar, and serving to maintain said springs in contact with the bottom of the cellar and thus to hold the end walls of the cellar in close contact with the journal, and further serving in the event of breakage of 95 the springs to prevent escape of the cellar from the journal box.

4. A journal box, comprising an outer box provided with perforations at its opposite sides; a cellar insertible within and removable from said box; a flat spring having upstanding arms at opposite sides and an intermediate raised bearing seat for the cellar, said parts being provided with aligned openings; and a cellar pin or bolt passing 100 through said openings, and serving to retain the cellar and the spring in place.

In testimony whereof I have signed my name to this specification.

THOMAS OGDEN.
